POWER UNIT

George O. Dean, Plainview, Tex.

Application October 27, 1936, Serial No. 107,894
Renewed July 26, 1938

2 Claims. (Cl. 170—24)

This invention relates to power plants, and it is primarily an object of the invention to provide an apparatus of this kind which is operated under the action of the wind and which is so constructed and arranged to provide economical means to provide power for operating pumps and the like.

The invention also has for an object to provide an apparatus of this kind which is particularly adapted for use in those portions of the country which are subjected to drought, the construction of the apparatus being such to assure the same having a maximum of efficiency irrespective of the direction in which the wind may be blowing.

A still further object of the invention is to provide an apparatus of this kind comprising a plurality of specially constructed vanes having rotation about a common vertical axis together with means whereby the apparatus may be readily and effectively maintained in desired assembly.

An additional object of the invention is to provide a device of this kind wherein each of the vanes is of a feathering type and wherein means are provided for controlling the action of the blades of a vane whereby the speed of rotation of the vanes may be regulated.

The invention consists in the details of construction and in the combination and arrangement of the several parts of my improved power plant whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in top plan and of somewhat a diagrammatic character of a power plant constructed in accordance with an embodiment of my invention;

Figure 2 is an enlarged vertical sectional view taken substantially on the line 2—2 of Figure 1, a second position of the blades of the vane being indicated by broken lines;

Figure 3 is an enlarged fragmentary sectional view illustrating the mounting for the mast of the apparatus as herein embodied;

Figure 4 is a view partly in section and partly in elevation of the apparatus as herein embodied.

As disclosed in the accompanying drawings, I

denotes a vertically disposed mast or shaft preferably tubular and which has threaded in its lower end portion a shank 2 carried by an extension cylindrical bearing block 3. This block 3 is relatively long and is received within a bushing 4 preferably embedded in a cementitious base or foundation 5. The lower or inserted end of the bushing 4 is closed, as at 4^a, and interposed between said lower closed end 4^a and the inserted end of the bearing block 3 is a relatively large anti-friction ball 6. The lower or inner end of the block 3 is concave as indicated by broken lines at 7 for proper coaction with the ball 6.

The upper portion of the bushing 4 has its bore transversely enlarged, as at 8, to provide a raceway 9 for the anti-friction members or ball bearings 10 which surround the bearing block 3 and thus further assure the rotation of the block 3 and, of course, the mast or shaft 1 with a minimum of frictional resistance.

The upper end of the bushing 4 is closed by a nut 11 threading into the upper portion of the bushing 4 and snugly surrounding the mast or shaft 1 and the adjacent portion of the bearing block 3. The bushing 4 is adapted to have placed therein a suitable lubricant, preferably grease.

The upper end of the shaft or mast 1 is closed by a cylindrical block 12 similar to the block 3 hereinbefore referred to and contacting with the upper concave face of the block 12 is a ball bearing 14. Disposed over this upper end of the mast or shaft 1 is an inverted cap 15, the lower portion of which being closed by an annular enlargement 16 surrounding the upper portion of the mast or shaft 1. This cap 15 is also intended to contain a suitable supply of lubricant, preferably grease.

The cap 15 at equidistantly spaced points there-around is provided with the outstanding eye 40 members 17 preferably four in number and to which are suitably connected the upper extremities of the guy lines 18. These lines 18 extend over and engage from above the posts or uprights 19 and are continued downwardly and connected by the turnbuckles 20 with the anchor lines 21. The posts 19 are of desired height and the upper extremity of each of said posts is preferably bifurcated with a guy line 18 passing through the kerf of the bifurcation.

The posts 19 have their lower ends suitably anchored within a cementitious base or foundation 22 and the posts 19 at their upper extremities 23 are connected by the bracing lines or cables 18^a whereby is further assured the desired effective 55

- mounting of the vertically disposed mast or shaft 1. The turnbuckles 20 permit ready tightening or loosening of the guy lines 18 as may be found necessary in order to maintain the required vertical position of the mast or shaft 1.
- Fixed to the mast or shaft 1 at desired points spaced therealong are the heads or enlargements 23 to which are bolted or otherwise rigidly attached as may be preferred the extremities of 10 the upper and lower arms 24 extending inwardly from each of the vanes V herein disclosed as four in number. These arms 24 as herein disclosed are in continuation of the upper and lower members 25 of each of the vanes V. The outer 15 extremities of the arms 25 are connected by an interposed vertical member 26 and connected to and interposed between the inner ends of the arms 25 is a second vertically disposed member 27. These members 25, 26 and 27 constitute the 20 frame structure of a vane and this frame structure is braced and reinforced by the crossed struts 28 extending diagonally across the interior of the frame and also by a central vertical strut 29.
- 25 The vertical members 26 and 27 at equidistantly spaced points rotatably support the shafts or pintles 30 for the feathering blades 31. An upper blade when in closed or working position laps and has coaction with the shaft or pintle 30 of the blade immediately therebelow while the lowermost blade 31 when in closed or working position laps and has contact with an upstanding flange 25a of the lower horizontal member 25. This feathering action of the blades 31 assures 35 effective and efficient operation of the apparatus, said blades being closed when the vane is moving with the wind and, of course, opening when the vane is travelling against the wind.
- The upper member 25 and the end members 40 26 and 27 of each of the vanes are provided with the upwardly and outwardly inclined flanges 32, the adjacent extremities of which are connected. These flanges 32 provide means to assure an effective driving action of the wind upon 45 the closed blades 31.
- Pivottally connected with the blades 31 of each 50 of the vanes is a pair of vertically disposed parallel rods 33 which operate to cause all of such blades to move in unison and in the same general direction. The upper extremity of each of the rods 33 has connected thereto a flexible member 34 which passes up and over a guide pulley 35 herein disclosed as operatively supported by a bracket 36 suitably secured to the upper flange 55 32. The cables or flexible members 34 of both of the rods 33 are operatively connected to a common cable or flexible member 37 with which are also operatively engaged the cables or flexible members 34 leading from the rods 33 of the diametrically opposed vane V. The common cable or flexible member 37 is of such a length that when the blades of one of the vanes are entirely closed the blades 31 of the diametrically opposed vane will be fully open. There is an advantage 60 in this arrangement as the action of the wind effecting the full closing of the blades 31 of one vane will positively assure the desired full opening of the blades 31 of the diametrically opposed vane.
- 65 The blades 31 of each of the vanes may be independently adjusted as may be required to regulate or control the desired rotation of the shaft 1 by providing a separate cable or flexible mem-

ber 38 connected to the common member 37. By pull on the member 38 an independent raising movement of the blades 31 of the vane may be accomplished or in another sense the extent of closing movement of the blades 31 of a vane V 5 may be controlled. Each of these members 38 is adapted to be connected in a conventional way with a conventional cleat 39 fixed to the mast or shaft 1.

The mast or shaft 1 has fixed thereto for rotation therewith a power take-off pulley 40 which is preferably positioned below the vane V and closely adjacent to the supporting foundation for the mast or shaft 1.

I do not wish to be understood as limiting myself in any way to the use to which may be put the power created by my improved plant although I wish to state that I particularly have in mind a cheap and economical apparatus for operating pumps for irrigating land in those sections of the 20 country subjected to drought, the water being preferably taken from wells although, of course, the source of water may come from any available stream.

From the foregoing description it is thought 25 to be obvious that a power plant constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several 30 parts herein shown in carrying out my invention in practice except as hereinafter claimed.

I claim:—

1. A power plant comprising a plurality of radially arranged vanes, means supporting said 40 vanes for rotary movement, each of said vanes comprising a plurality of blades, horizontally disposed pivots for each blade at one edge thereof, means secured to the free edges of the blades connecting the blades of each vane together for 45 movement in unison, and flexible means connecting the blades of diametrically opposed vanes together in such a manner that movement of the blades of one vane to closed position will positively move the blades of the opposed vane to 50 open position.

2. A power plant comprising a plurality of radially arranged vanes, means supporting said 55 vanes for rotary movement, each of said vanes comprising open frame structure including marginal plates disposed in divergent relation with respect to the movement of air, the divergent side of the frame constituting the intake side of the frame, a plurality of blades, horizontally disposed pivot members for said blades secured to the convergent end of the frame, a vertically disposed connecting bar pivotally secured to the free edges of said blades whereby said blades will rock in unison on said pivot members, a bracket secured to each frame at the upper edge thereof, 60 a pulley carried by each bracket, and a flexible member secured at the ends thereof to diametrically opposed connecting bars and trained over said pulleys whereby downward movement of the blades of one vane under the action of gravity 65 and wind pressure will simultaneously raise diametrically opposed blades.

GEORGE O. DEAN.
